AUGUST G. ZIESING, OF WEEHAWKEN, NEW JERSEY.

Letters Patent No. 100,833, dated March 15, 1870.

IMPROVEMENT IN LOCKS FOR SHIPS' PUMPS.

The Schedule referred to in these Letters Patent and making part of the same

To all whom it may concern:

Be it known that I, AUGUST G. ZIESING, of Weehawken, in the county of Hudson, and State of New Jersey, have invented a new and improved Lock for Ships' Pumps; and I do hereby declare that the following is a full, clear, and exact description thereof, which will enable others skilled in the art to make and use the same, reference being had to the accompanying drawings forming part of this specification, in which the drawing represents a sectional side view of my invention.

This invention has for its object to provide a device by means of which the pumps in ships can be locked, to prevent their being used while so locked. For parties who desire to buy ships it is one of the most important items to ascertain whether the vessels have sound bottoms, or whether they draw water. At present it is a common practice with dishonest persons to secretly apply the pumps and reduce the water in the hold, in case the same should be rising during a pending bargain. If the pumps are effectively locked this fraudulent practice will be defeated, and less risk incurred in the buying or hiring of vessels.

A, in the drawing, represents the barrel or cylinder of a ship's pump. The same is of suitable kind.

Before applying my improved lock, the pump-gear, *i. e.*, the plunger-rod and valve must be removed from the barrel.

The lock consists of a perforated plate, B, secured to the lower end of a rod, C.

This plate is let into the barrel, and the rod is then, by means of a chain, D, or other suitable device, locked to the upper end of the barrel to prevent the displacement of the plate B.

For this purpose a padlock, E, or other equivalent safety apparatus, is employed.

The water in the hold can be measured through the holes in the plate B. A party desiring to ascertain the value of a ship will remove the pump-gearing, insert the plate B in the pump-barrel and lock it thereto, measure the height of water in the hold at the time of locking, and again after several hours or days.

Without picking the lock the pump can, in the meantime, not be applied.

Having thus described my invention,

I claim as new, and desire to secure by Letters Patent—

The perforated plate B and rod C, arranged as a lock for ships' pumps, substantially as herein shown and described.

A. G. ZIESING.
